DESIGN FOR A GAS CONTROL KNOB FOR STOVES AND THE LIKE

Donald E. Stewart, Grandville, Mich., assignor to
Winters & Crampton Corporation, Grandville,
Mich., a corporation of Michigan

Application September 4, 1945, Serial No. 121,803

Term of patent 7 years

(Cl. D81—25)

To all whom it may concern:

Be it known that I, Donald E. Stewart, a citizen of the United States, residing at Grandville, in the county of Kent and State of Michigan, have invented a new, original, and ornamental Design for Gas Control Knob for Stoves and the like, of which the following is a specification, reference being had to the accompanying drawing, forming part thereof.

Fig. 1 is a perspective view of a gas control

knob for stoves and the like showing my new design.

Fig. 2 is a front elevation of the same.

Fig. 3 is a side elevation of the same, and

Fig. 4 is a bottom view of the same.

I claim:

The ornamental design for a gas control knob for stoves and the like, substantially as shown.

DONALD E. STEWART.
